UNITED STATES PATENT OFFICE.

GEORGE V. NAUERTH, OF CINCINNATI, OHIO.

FILE FOR LETTERS.

SPECIFICATION forming part of Letters Patent No. 271,258, dated January 30, 1883.

Application filed March 6, 1882. (No model.) Patented in Canada April 11, 1882, No. 14,567, and in England April 11, 1882, No. 1,720.

To all whom it may concern:

Be it known that I, GEORGE V. NAUERTH, of the city of Cincinnati, Hamilton county, and State of Ohio, have invented certain new and useful Improvements in Files for Letters and other Papers, of which the following is a specification.

The nature of my invention and of its various features and the several advantages resulting therefrom are fully set forth in the following specification and claims.

Referring to the drawings forming part of this specification, Figure 1 is a perspective view of the file with the cover raised to the position it occupies when the papers are to be examined. Fig. 2 is a perspective view of the file with the cover in the position to hold the letters or papers in the file. Figs. 3, 4, and 5 are views of detached portions of said file.

20 The file consists of a case having the sides or ends A, back B, bottom C, and removable cover D.

In the case or box is usually placed a series of index-leaves, E, between which leaves the 25 papers to be filed are placed. These leaves are preferably retained in the case by the pins a, which are fastened to the bottom of the case, near the back B, the leaves being provided with openings b, through which the pins a 30 pass. These pins are respectively provided at or near their top with a suitable projection, m, which prevents the leaves from being accidentally slipped off the pins. These projections are removable, and in the present instance 35 consist of nuts, one of which is screwed onto the upper end of each pin.

To the inner faces of the ends A are secured the racks d and e. These racks are suitably secured in position in the case, and for the 40 purpose of the better securing them in place are preferably dovetailed, as shown in Figs. 3 and 4, and fit into correspondingly dovetailed recesses in the ends A.

To each rack, at or near its lower end, is attached a lug, f, which rests against the lower edge of the ends A. The rack is preferably placed in the dovetailed recess in the following manner, viz: placing the upper end of the rack in the bottom end of the dovetailed recess and driving the rack upward to position. 45 This lug f holds the racks d and e securely in

position, preventing them from being detached from the end A by any upward strain.

To either end of the cover D are secured the lugs g, which are preferably formed as shown, 55 by staples driven into the ends of the cover D, and the lugs at either end of the cover are separated by a distance equal to the distance between the racks d and e.

In the rear edge of the cover D are formed 60 the notches F, which correspond to the position of the pins a, and which are of sufficient depth to permit the cover, when raised to the position shown in Fig. 1, to be so raised without interfering with the pins a. When the cover 65 D is to be secured in the box it is placed therein, the lugs g being in the rear of the racks d and e. The cover is now pressed down upon the index-leaves E, at the same time that it is pushed forward, when the lugs g will enter 70 the various racks d and e, and the cover is thus held firmly down on the index-leaves.

The cover is prevented from being pushed too far forward by the guards h on the front edge of the racks d, against which the forward 75 lugs g strike.

It is only necessary that two of the racks—one on either side of the case—be provided with the guard; but, if desired, all of the racks may be so provided. When the cover is to be 80 raised it is slid toward the back B, a thumb-hole, H, being formed in the cover for greater convenience in lifting the cover.

The notches F, which correspond to the position of the pins a, allow the cover to be slid 85 back till it comes in contact with the back B, and a space being left between the back B and the rear edges of the index-leaves, the cover is raised and allowed to drop into this space, when it assumes the position shown in Fig. 1, 90 when the papers may be readily examined. Moving the cover toward the back of the case before it can be raised is much more convenient than to move it forward, as has heretofore been done, and therefore makes the file more 95 practical for business purposes. The peculiar formation of the racks secures them firmly in position, and thus the cover will be held firmly down upon the index-leaves.

The various features of my invention are 100 preferably employed in conjunction with each other; but they, any one or more of them, may

be employed independently of the others, or together, as desired, and yet fall within the scope of my invention.

What I claim as new and of my invention, and desire to secure by Letters Patent, is—

- 5 1. In a file for letters or other papers, the combination of the cover D, provided with the lugs g, and the case provided with the racks d e, two or more of said racks being provided
- 10 with guards h, substantially as and for the purposes specified.

2. In a file for letters or other papers, the combination of the cover D, provided with the lugs g, the notches F, and the case provided with pins a and racks d e, the front edge of 15 the racks d being provided with guards h, substantially as and for the purposes specified.

GEO. V. NAUERTH.
